UNITED STATES PATENT OFFICE.

CHARLES R. BARRETT AND EMIL A. SAMUEL, OF CHICAGO, ILLINOIS; SAID SAMUEL
ASSIGNOR TO SAID BARRETT.

MACHINE FOR FORMING LOOPS ON COILED SPRINGS.

1,114,846.

Specification of Letters Patent. Patented Oct. 27, 1914.

Application filed February 13, 1914. Serial No. 818,598.

To all whom it may concern:

Be it known that we, CHARLES R. BARRETT and EMIL A. SAMUEL, citizens of the United States of America, and residents of Chicago, in the county of Cook and State of Illinois, have invented certain new and useful Improvements in Machines for Forming Loops on Coiled Springs, of which the following is a specification.

This invention relates to machines for forming loops on coiled springs, and in which a portion of each end coil of the spring is bent into right-angle relation to the body portion of the spring to provide an attaching hook or loop for the same. An example of such machine is the subject matter of Letters Patent No. 971,238, dated September 27, 1910, to Charles R. Barrett. And the present improvement has for its object to provide a simple and automatically operating mechanism by which sections of coiled springs are fed to a pair of alternately operating loop-forming appliances adapted to bend the respective end coils of the section of spring operated on, into attaching hooks or loops.

A further object is to provide means for automatically turning the section of spring, and to attain a correct positioning of the end coils of the same with relation to the loop-forming appliances, and thus insure the formation of loops or hooks on said section of coiled spring in an effective and perfect manner, all as will hereinafter more fully appear.

In the accompanying drawings: Figure 1 is a plan view illustrating the general arrangement of parts in the present invention. Fig. 2 is a longitudinal section on line $x-x$, Fig. 1. Fig. 3 is an enlarged transverse section on line $x'-x'$, Fig. 2. Fig. 4 is a detail perspective view of the section of coiled spring, as fed to the machine, and before the loop-forming operation. Fig. 5 is a similar view of said section of spring after the loop-forming operations have taken place. Fig. 6 is a fragmentary top view of the under and front portion of the machine, the carrying frame, etc., of the rotary loop-forming heads being removed. Fig. 7 is a detail elevation of one of the spring positioning mandrels, and some of its accessories.

Fig. 8 is a detail sectional view of the same. Fig. 9 is an elevation of the sleeve or head of the other positioning mandrel. Fig. 10 is a detail sectional elevation of the last-mentioned positioning mandrel, and some of its accessories. Fig. 11 is a detail plan view of the same. Fig. 12 is an enlarged fragmentary longitudinal section of the front portion of the machine, on line $x-x$, Fig. 1. Fig. 13 is a detached perspective view of the upper sliding carrier and one of the upper spring-holding jaws. Fig. 14 is a detail perspective view of the front portion of the carrying head of the aforesaid upper sliding carrier and its accessories.

Similar reference numerals indicate like parts in the several views.

Referring to the drawings, 1 represents the supporting bed or base plate of the machine, upon which is carried the series of standards and pedestals of the present mechanisms, as follows: 2 are a pair of standards centrally disposed at the rear of the bed 1, and provided with bearings for the primary driving shaft 3, and for the lower longitudinal countershaft 4, of the present mechanism. 5 is a pedestal centrally disposed at the mid-length of the bed 1, and provided with bearings for the upper longitudinal countershaft 6, and with a guideway for the longitudinally reciprocating carrying head 7, of the upper spring-holding jaws herein-after described. 8 is a pedestal centrally disposed at the forward end of the bed 1, and provided with a bearing for the forward end of the above-mentioned countershaft 4, and with guideways for the longitudinally reciprocating slide 9 of the preliminary feeding mechanism by which the springs are serially fed to the pair of loop-forming appliances. 10 are a pair of pedestals secured to the bed 1, in lateral relation to the loop-forming appliances above referred to, and provided with slideways for the headstocks 11, in which are journaled the herein-after described rotary and transversely reciprocating spring positioning mandrels 12 and 13, of the present invention. 14 are a pair of standards disposed in adjacent parallel relation to the pedestals 10, above described, and provided with journal bearings for the shafts 15 and 16 of the here-

inafter described cams by which reciprocation is imparted to the headstocks 11 of the spring positioning mandrels 12 and 13 above referred to. 17 is a feeding chute secured to the pedestal 8, in a transverse and inclined direction, and adapted to contain a supply of the sections of coiled springs to be operated on. 18 is an inclined bar secured to and reciprocating with the slide 9, above referred to, and provided with a spring finger 19 and a stop finger 20, arranged in separated relation, and extending longitudinally into the path of the sections of coiled springs contained in the feeding chute 17. 15 In the operation of such parts, a section of coiled spring normally rests against the stop finger 20, while the next adjacent section of coiled spring is yieldingly held by the spring finger 19. With a forward travel 20 of the parts along with the automatically actuated slide 9, the stop finger 20 moves from beneath its section of coiled spring, and permits the same to slide down against a lateral stop plate 21 carried by the slide 9, aforesaid, and onto the initial feeding mechanism hereinafter described. During such forward travel of the parts, the spring finger 19 maintains yielding holding engagement with its section of coiled spring, to prevent 25 any downward movement of the same. With a succeeding rearward movement of the aforesaid parts, the stop finger 20 moves into the path of the sections of coiled springs in the chute 17 and the spring finger 19 moves out of engagement with its section of coiled spring, allowing the same to slide 30 down upon the stop finger 20, for a repetition of the cycle of operations just described. 22 is a longitudinally disposed carrier 40 pivoted at its forward end in the slide 9 aforesaid, and having at its rear end a concave recess adapted to receive the section of coiled spring after the same is released by the stop finger 20, as above described. The 45 rear end of said carrier 22, has a downwardly extending heel 23, that is adapted to ride upon the horizontal bottom of the recess in the slide 9 in which said carrier is disposed, to be maintained in proper position 50 during the main portion of the rearward travel of said carrier 22. In the present construction the rear portion of the aforesaid recess in the slide 9, is cut away at 24, to permit a downward pivotal movement 55 of the carrier 22, as the section of coiled spring is taken from said carrier by the hereinafter described forward pair of holding jaws of the loop-forming appliances. 25 is a spring tending to yieldingly maintain 60 the carrier 22 in its normally horizontal position. 26 is a cam wheel on the forward end of the lower countershaft 4, for operative engagement with a cam stud on the slide 9, 65 and adapted to impart an intermittent re-

ciprocation to said slide, in the practical operation of the mechanism.

27 is an anvil or projection extending rearwardly from the pedestal 8, and having a horizontal face upon which the sections of coiled springs move rearwardly and are held 70 during the loop-forming operations hereinafter described.

28 and 29 are abutment lugs located at opposite sides of the anvil 27, and disposed in longitudinal spaced relation to each other, so as to be in operative and individual relation to the pair of loop-forming heads and accessories hereinafter described. The abutment lugs 28, 29 are adapted to form stops 75 for the adjacent ends of the sections of coiled springs, while the same are circularly positioned, and while the end coils of said sections are bent at right-angles to the main portions of said sections, as hereinafter more 80 fully described.

30 is the movable upper jaw of the first pair of holding jaws of the present construction. Said jaw 30 is attached to a vertically sliding head 31, which has movement 90 in a suitable guide opening in the longitudinally sliding head 7, heretofore described. The vertically sliding head 31 is common to the said upper jaw 30 of the first pair of holding jaws, and to a counterpart movable 95 upper jaw of the second pair of holding jaws, hereinafter described. And the connection of said jaws to the sliding head 31 is preferably of an adjustable nature and attained by means of the usual guide 100 grooves, guide slots and holding bolts, as shown.

32 is a spring interposed between the carrying head 7 and the sliding head 31, and adapted to yieldingly move the head 31 in 105 an upward direction.

33 is a cam disk secured to the forward end of the upper countershaft 6, and having bearing against the cam roller 34 carried by the sliding head 31, and adapted to impart 110 vertical movement to the same in a downward direction. Movement in an upward direction is attained by the spring 32, above described.

35 is a cam wheel near the rear end of the upper countershaft 6, having engagement 115 with a cam stud 36 on the slide 7, and adapted to impart positive intermittent reciprocal motion to said slide.

37 is the movable upper jaw of the second pair of holding jaws of the present construction. Said jaw 37 is a counterpart of the jaw 30 above described, and is carried by the vertically sliding head 31, aforesaid. The movable lower jaws of the first and second pairs of holding jaws, are of a single 125 piece construction and in detail comprise a main body portion 38, formed with a series of upwardly extending bars or teeth 39, preferably three in number as shown, and 130

which are disposed in vertical guide orifices formed therefor in the anvil or projections 27, above described.

49 is a cam disk secured to the lower countershaft 4, and having bearing against the cam roller 41, carried by the main body 38 of the lower movable jaws above described, and adapted to impart intermittent upward movement to the same, in the actual 10 operation of the mechanism.

42 is a spring interposed between the anvil 27, and the main body portion 38 of the lower movable jaws, for the purpose of depressing said jaws after the same are raised 15 by the cam disk 40, aforesaid.

In the present construction, the countershafts 4 and 6, before described, receive simultaneous rotation from the primary driving shaft 3, through pinions 43 and 44 on 20 said shaft 3, which pinions mesh with and impart motion to gear wheels 45 and 46 on the respective countershafts 4 and 6, as shown in Fig. 2.

47 and 48 are a pair of loop-forming heads disposed in spaced lateral and longitudinal relation to each other, so as to be individual to the respective first and second pairs of holding jaws 30, 37 and 38, heretofore described. Said loop-forming heads 30 comprise main body portions or hubs 47, 48, and radial bending jaws 49, 50, which are adapted to revolve in circular paths. The function and operation of the bending jaws 49, 50 is similar to that of the bending jaw 35 of the aforesaid Barrett Patent No. 971,238, and as in said patented construction, said bending jaws are adapted to engage the outer coils of the section of coiled spring operated on, and bend said end coils at 40 right-angles to the body of the coiled spring, to provide attaching loops or hooks at the respective ends of said coiled spring section.

51 and 52 are the carrying shafts of the 45 loop-forming heads 47, 48, aforesaid. Said shafts are journaled in the lower ends of pairs of vertical bracket plates 53, 54, secured at their upper ends to the standard 5, in a laterally adjustable manner, by bolts 50 and elongated slots, as illustrated more particularly in Fig. 3.

55 and 56 are two trains of gear wheels, by means of which rotation in opposite direction is transmitted from the countershaft 55 4, to the carrying shafts 51 and 52 of the loop forming heads 47, 48 above described.

The pair of spring positioning mandrels 12 and 13 heretofore referred to, are disposed in spaced longitudinal relation to 60 each other, so as to have individual operative relation to one another of the pairs of holding jaws 30, 37 and 38, and loop-forming heads 47, 48 aforesaid, and in the present improvement have a detail construction 65 as follows: 57 is a sleeve having sliding

movement on a reduced inner end of the positioning mandrel 12 and held from independent rotation thereon by a pin 58, and elongated slot 59, as illustrated more particularly in Figs. 7 and 8. The inner and 70 free end of said sleeve 57 is adapted to engage in the bore of the section of coiled spring operated on, and with a view to attain proper frictional engagement of the parts, said inner end of the sleeve 57 will be 75

of the conical form shown in Figs. 7 and 8. 60 is a spring tending to yieldingly force the sleeve 57 into the above described frictional engagement with the section of coiled spring operated on, and so that in the normal 80 rotation of the positioning mandrel 12, the said sleeve 57 will cause a partial rotation of the spring section operated on, until the extreme end of an outer coil of said spring section is brought against an edge of 85 the abutment lug 28, which prevents further rotation of the spring section, and insures its proper position for the subsequent loop-forming operation of the loop-forming head 47—49, aforesaid. 61 is a head or sleeve 90 having sliding movement on a reduced inner end of the positioning mandrel 13. Said sleeve 61 is held on said mandrel by a transverse pin 62, intersecting an elongated peripheral groove 63, in the mandrel, as 95 shown in Fig. 10, the construction being adapted to permit of an independent rotation of the sleeve, as well as a limited longitudinal movement of the same. 64 are friction serrations formed in the face of an enlarged rear portion of the sleeve 61, which are adapted for frictional engagement with spring friction studs or plugs 65, carried by the mandrel 13, as shown on Figs. 10 and 100 11.

Such construction is adapted to permit a continued and independent rotation of the mandrel 13, when in the operation of the mechanism, the sleeve 61 is forcibly held from rotation. 66 is a ratchet formation on the front and free end of the sleeve 105 110 61, and adapted to engage the loop or hook of the section of coiled spring operated on, and as illustrated in Fig. 10. With the described construction, the normal rotation of the positioning mandrel 13 is adapted to 115 impart a partial rotation to the section of coiled spring operated on, and until the extreme end of the outer coil at the other end of said section of coiled spring is brought against an edge of the abutment lug 29, 120 which in turn prevents any further rotation of said spring section and insures its proper position for the subsequent and final loop or hook forming operation of the loop-forming head 48—50, aforesaid. 67 is a bevel gear carried by the countershaft 4, and having operative engagement with bevel gears 68, 69, on the inner ends of the transverse cam shafts 15 and 16, heretofore described.

70, 71 are gear wheels carried on the outer 125 130

ends of the aforesaid cam shafts 15 and 16, and having operative engagement with wide face pinions 72, 73 on the outer ends of the positioning mandrels 12 and 13, to impart 5 rotation to the same. 74, 75 are cam drums on the cam shafts 15 and 16, the cam grooves of which have operative engagement with cam studs 76, 77 on the reciprocating headstocks 11 of the positioning 10 mandrels 12 and 13, to impart limited intermittent reciprocation to the same.

The operation of the present machine is as follows: Sections of coiled springs of the required length are serially released from 15 the feeding chute 17, by the intermittent operation of the spring and stop fingers 19 and 20, as heretofore described in detail. The section of coiled spring as released, descends against the lateral stop plate 21, and is received by the concave rear end of the carrier 22, and in the rearward reciprocation of the carrier is carried back into position beneath the upper movable jaw 30 of the first pair of holding jaws, and is in turn engaged and 25 held thereby. Immediately previous to such engagement, the first positioning mandrel 12 reciprocates transversely to bring its sleeve 57 into frictional engagement with the section of coiled spring, to cause a partial rotation of the same and attain the required "positioning", as heretofore set forth in detail. Immediately following such positioning of the section of coiled spring, the aforesaid first pair of holding jaws come into 30 holding engagement with said section of coiled spring, and following such holding engagement, the radial bending jaw 49 of the first loop-forming head 47, engages an outer coil at the other end of said section of 40 coiled spring, and bends the same over the abutment lug 28, into right-angle relation, and provides the required spring-attaching loop or hook, as heretofore set forth in the description of the mechanism. The upper 45 holding jaw 30 of the first pair of holding jaws, through the rearward movement of the reciprocating carrying head 7, then moves said section of coiled spring backward along the anvil 27, and leaves said section 50 of spring in the engaging zone of the second pair of holding jaws 37-39. The second positioning mandrel 13 then reciprocates transversely, to bring its sleeve 61 into engagement with the loop or hook previously 55 formed on the section of coiled spring, to cause a partial rotation of said spring section, and attain the required "positioning" heretofore described. Immediately following such second positioning of the section 60 of coiled spring, the aforesaid second pair of holding jaws are brought into holding engagement with said section of coiled spring, and following such holding engagement, the radial bending jaw 50 of the second loop-forming head 48, engages the outer coil at

the other end of said section of coiled spring, and bands the same over the abutment lug 29, into right-angle relation, and provides a spring-attaching hook or loop at the other end of said spring section to that first described. Simultaneously with the operation of the second loop-forming operations just described, the loop-forming mechanism first described is effecting a loop-forming operation on a second section of coiled spring, the 70 operations continuing during the practical use of the machine, and with the completed springs being automatically discharged at the rear end of the anvil 27.

Having thus fully described our said invention, what we claim as new and desire to secure by Letters Patent, is:—

1. A mechanism for forming loops on sections of coiled springs, comprising a feeding chute, a longitudinally reciprocating carrier, 85 an anvil disposed to the rear of said carrier and provided with a lateral abutment, a rotary looper head arranged above said anvil, and means for operating the carrier and looper head in unison, substantially as 90 set forth.

2. A mechanism for forming loops on sections of coiled springs, comprising a feeding chute, a longitudinally reciprocating carrier, a spring finger and a stop finger associated 95 with said chute in spaced relation and moving with said carrier, an anvil disposed to the rear of said carrier and provided with a lateral abutment, a looper head arranged above said anvil, and means for operating the 100 carrier and looper head in unison, substantially as set forth.

3. A mechanism for forming loops on sections of coiled springs, comprising a feeding chute, a longitudinally reciprocating carrier, 105 an anvil disposed to the rear of said carrier and provided with a lateral abutment, a positioning means adapted to impart partial rotation to the section of spring operated on, a looper head arranged above the anvil aforesaid, and means for operating the carrier, 110 looper head and positioning means in unison, substantially as set forth.

4. A mechanism for forming loops on sections of coiled springs, comprising a feeding chute, 115 a longitudinally reciprocating carrier, an anvil disposed to the rear of said carrier and provided with a lateral abutment, a laterally disposed positioning means adapted for operative engagement with an end of 120 the section of spring operated on and adapted to impart partial rotation thereto, a looper head arranged above the anvil aforesaid, and means for operating the carrier, looper head and positioning means in unison, substantially as set forth.

5. A mechanism for forming loops on sections of coiled springs, comprising a feeding chute, a longitudinally reciprocating carrier, a spring finger and a stop fin- 130

ger associated with said chute in spaced relation and moving with said carrier, an anvil disposed to the rear of said carrier and provided with a lateral abutment, a positioning means adapted to impart a partial rotation to the section of spring operated on, a looper head arranged above the anvil aforesaid, and means for operating the carrier, looper head and positioning means in unison, substantially as set forth.

6. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with a lateral abutment, a laterally disposed positioning means adapted for operative engagement with an end of the section of spring operated on and adapted to impart partial rotation thereto, a looper head arranged above the anvil aforesaid, and means for operating the carrier, looper head and positioning means in unison, substantially as set forth.

7. A mechanism for forming loops on sections of coiled springs, comprising a feeding chute, a longitudinally reciprocating carrier, an anvil disposed to the rear of said carrier and provided with a lateral abutment, a laterally disposed positioning means comprising a revolute and laterally reciprocating mandrel and a sleeve on the end of said mandrel adapted for operative engagement with an end of the section of the spring operated on and adapted to impart partial rotation thereto, a looper head arranged above the anvil aforesaid, and means for operating the carrier, looper head and positioning means in unison, substantially as set forth.

8. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with a lateral abutment, a laterally disposed positioning means comprising a revolute and laterally reciprocating mandrel and a sleeve on the end of said mandrel adapted for operative engagement with an end of the section of spring operated on and adapted to impart partial rotation thereto, a looper head arranged above the anvil aforesaid, and means for operating the carrier, looper head and positioning means in unison, substantially as set forth.

9. A mechanism for forming loops on sections of coiled springs, comprising a feeding chute, a longitudinally reciprocating carrier, an anvil disposed to the rear of said carrier and provided with a lateral abutment,

a rotary looper head arranged above said anvil, a pair of vertically moving holding jaws associated with said anvil, and means for operating the carrier, looper head and holding jaws in unison, substantially as set forth.

10. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with a lateral abutment, a looper head arranged above said anvil, a pair of vertically moving holding jaws associated with said anvil, and means for operating the carrier, looper head and holding jaws in unison, substantially as set forth.

11. A mechanism for forming loops on sections of coiled springs, comprising a feeding chute, a longitudinally reciprocating carrier, an anvil disposed to the rear of said carrier and provided with a lateral abutment, a rotary looper head arranged above said anvil, a positioning means adapted to impart partial rotation to the section of spring operated on, a pair of vertically moving holding jaws associated with said anvil, and means for operating the carrier, looper head, positioning means and holding jaws in unison, substantially as set forth.

12. A mechanism for forming loops on sections of coiled springs, comprising a feeding chute, a longitudinally reciprocating carrier, an anvil disposed to the rear of said carrier and provided with a lateral abutment, a rotary looper head arranged above said anvil, a laterally disposed positioning means adapted for operative engagement with an end of the section of spring operated on and adapted to impart partial rotation thereto, a pair of vertically moving holding jaws associated with said anvil, and means for operating the carrier, looper head, positioning means and holding jaws in unison, substantially as set forth.

13. A mechanism for forming loops on sections of coiled springs, comprising a feeding chute, a longitudinally reciprocating carrier, an anvil disposed to the rear of said carrier and provided with a lateral abutment, a rotary looper head arranged above said anvil, and means for operating the carrier and looper head in unison, arranged above said anvil, a laterally disposed positioning means adapted for operative engagement with an end of the section of spring operated on and adapted to impart partial rotation thereto, a pair of vertically moving holding jaws associated with said anvil, and means for operating the carrier, looper head, positioning means and holding jaws in unison, substantially as set forth.

14. A mechanism for forming loops on

sections of coiled springs, comprising a feeding chute, a longitudinally reciprocating carrier, an anvil disposed to the rear of said carrier and provided with a lateral abutment, a rotary looper head arranged above said anvil, a pair of vertically moving holding jaws associated with said anvil, means for imparting intermittent longitudinal reciprocation to the upper holding jaw, and means for operating the carrier, looper head and holding jaws in unison, substantially as set forth.

15. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with a lateral abutment, a looper head arranged above said anvil, a pair of vertically moving holding jaws associated with said anvil, means for imparting intermittent longitudinal reciprocation to the upper holding jaw, and means for operating the carrier, looper head and holding jaws in unison, substantially as set forth.

16. A mechanism for forming loops on sections of coiled springs, comprising a feeding chute, a longitudinally reciprocating carrier, an anvil disposed to the rear of said carrier and provided with a lateral abutment, a rotary looper head arranged above said anvil, a positioning means adapted to impart partial rotation to a section of spring operated on, a pair of vertically moving holding jaws associated with said anvil, means for imparting intermittent longitudinal reciprocation to the upper holding jaw, and means for operating the carrier, looper head, positioning means and holding jaws in unison, substantially as set forth.

17. A mechanism for forming loops on sections of coiled springs, comprising a feeding chute, a longitudinally reciprocating carrier, an anvil disposed to the rear of said carrier and provided with a lateral abutment, a rotary looper head arranged above said anvil, a laterally disposed positioning means adapted for operative engagement with an end of the section of spring operated on and adapted to impart partial rotation thereto, a pair of vertically moving holding jaws associated with said anvil, means for imparting intermittent longitudinal reciprocation to the upper holding jaw, and means for operating the carrier, looper head, positioning means and holding jaws in unison, substantially as set forth.

18. A mechanism for forming loops on sections of coiled springs, comprising a feeding chute, a longitudinally reciprocating carrier, a spring finger and a stop finger associated with said chute in spaced relation and moving with said carrier, an anvil dis-

posed to the rear of said carrier and provided with a lateral abutment, a looper head arranged above said anvil, a laterally disposed positioning means adapted for operative engagement with an end of the section of spring operated on and adapted to impart partial rotation thereto, a pair of vertically moving holding jaws associated with said anvil, means for imparting intermittent longitudinal reciprocation to the upper holding jaw, and means for operating the carrier, looper head, positioning means and holding jaws in unison, substantially as set forth.

19. A mechanism for forming loops on sections of coiled springs, comprising an anvil having lateral abutment lugs, a pair of loop-forming heads associated with said anvil and disposed one in advance of the other, means for intermittently feeding sections of coiled springs along said anvil, and means for holding said sections of spring during the operation of the loop-forming heads, substantially as set forth.

20. A mechanism for forming loops on sections of coiled springs, comprising an anvil having lateral abutment lugs, a pair of loop-forming heads associated with said anvil and disposed one in advance of the other, means for intermittently feeding sections of coiled springs along said anvil, pairs of individual holding jaws disposed one in advance of the other, and means for operating the feeding means, loop-forming heads and holding jaws in unison, substantially as set forth.

100
21. A mechanism for forming loops on sections of coiled springs, comprising an anvil having lateral abutment lugs, a pair of loop-forming heads associated with said anvil and disposed one in advance of the other, means for intermittently feeding sections of coiled springs along said anvil, duplicate positioning means adapted to impart partial rotation to the sections of springs operated on, and means for holding said sections of springs during the operation of the loop-forming heads, substantially as set forth.

110
22. A mechanism for forming loops on sections of coiled springs, comprising an anvil having lateral abutment lugs, a pair of loop-forming heads associated with said anvil and disposed one in advance of the other, means for intermittently feeding sections of coiled springs along said anvil, pairs of individual holding jaws disposed one in advance of the other, means for imparting intermittent longitudinal reciprocation to the upper holding jaws, and means for operating the feeding means, loop-forming heads and holding jaws in unison, substantially as set forth.

115
120
125
130
23. A mechanism for forming loops on sections of coiled springs, comprising a feeding chute, a longitudinally reciprocating

carrier, an anvil disposed to the rear of said carrier and provided with lateral abutment lugs, a pair of loop-forming heads arranged above said anvil and disposed one in advance of the other, and means for operating the carrier and looper heads in unison, substantially as set forth.

24. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with lateral abutment lugs, a pair of loop-forming heads arranged above said anvil and disposed one in advance of the other, and means for operating the carrier and looper heads in unison, substantially as set forth.

25. A mechanism for forming loops on sections of coiled springs, comprising a feeding chute, a longitudinally reciprocating carrier, an anvil disposed to the rear of said carrier and provided with lateral abutment lugs, a pair of positioning means adapted to impart partial rotation to the sections of springs operated on, a pair of loop-forming heads arranged above said anvil and disposed one in advance of the other, and means for operating the carrier, looper heads and positioning means in unison, substantially as set forth.

26. A mechanism for forming loops on sections of coiled springs, comprising a feeding chute, a longitudinally reciprocating carrier, an anvil disposed to the rear of said carrier and provided with lateral abutment lugs, a pair of longitudinally disposed positioning means adapted for operative engagement with ends of the sections of springs operated on to impart partial rotation thereto, a pair of loop-forming heads arranged above said anvil and disposed one in advance of the other, and means for operating the carrier, looper heads and positioning means in unison, substantially as set forth.

27. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with lateral abutment lugs, a pair of positioning means adapted to impart partial rotation to the sections of springs operated on, a pair of loop-forming heads arranged above said anvil and disposed one in advance of the other, and means for operating the carrier, looper heads and positioning means in unison, substantially as set forth.

28. A mechanism for forming loops on sections of coiled springs, comprising a feed-

ing chute, a longitudinally reciprocating carrier, a spring finger and a stop finger associated with said chute in spaced relation and moving with said carrier, an anvil disposed to the rear of said carrier and provided with lateral abutment lugs, a pair of laterally disposed positioning means adapted for operative engagement with the ends of sections of springs operated on to impart partial rotation thereto, a pair of loop-forming heads arranged above said anvil and disposed one in advance of the other, and means for operating the carrier, looper heads and positioning means in unison, substantially as set forth.

29. A mechanism for forming loops on sections of coiled springs, comprising a feeding chute, a longitudinally reciprocating carrier, an anvil disposed to the rear of said carrier and provided with lateral abutment lugs, a pair of loop-forming heads arranged above said anvil and disposed one in advance of the other, a pair of laterally disposed positioning means comprising revoluble and laterally reciprocating mandrels and sleeves on the ends of said mandrels for operative engagement with the ends of the sections of springs operated on and adapted to impart partial rotations thereto, and means for operating the carrier, looper heads and positioning means in unison, substantially as set forth.

30. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with lateral abutment lugs, a pair of loop-forming heads arranged above said anvil and disposed one in advance of the other, a pair of laterally disposed positioning means comprising revoluble and laterally reciprocating mandrels and sleeves on the ends of said mandrels for operative engagement with the ends of sections of springs operated on and adapted to impart partial rotation thereto, and means for operating the carrier, looper heads and positioning means in unison, substantially as set forth.

31. A mechanism for forming loops on sections of coiled springs, comprising a feeding chute, a longitudinally reciprocating carrier, an anvil disposed to the rear of said carrier and provided with lateral abutment lugs, a pair of loop-forming heads arranged above said anvil and disposed one in advance of the other, a pair of vertically moving holding jaws associated with said anvil, and means for operating the carrier, looper heads and holding jaws in unison, substantially as set forth.

32. A mechanism for forming loops on sections of coiled springs, comprising a feed-

ing chute, a longitudinally reciprocating carrier, a spring finger and a stop finger associated with said chute in spaced relation and moving with said carrier, an anvil disposed to the rear of said carrier and provided with lateral abutment lugs, a pair of loop-forming heads arranged above said anvil and disposed one in advance of the other, a pair of vertically moving holding jaws associated with said anvil, and means for operating the carrier, looper heads and holding jaws in unison, substantially as set forth.

33. A mechanism for forming loops on sections of coiled springs, comprising a feeding chute, a longitudinally reciprocating carrier, an anvil disposed to the rear of said carrier and provided with lateral abutment lugs, a pair of positioning means adapted to impart partial rotations to the sections of springs operated on, a pair of loop-forming heads arranged above said anvil and disposed one in advance of the other, a pair of vertically moving holding jaws associated with said anvil, and means for operating the carrier, looper heads, positioning means and holding jaws in unison, substantially as set forth.

34. A mechanism for forming loops on sections of coiled springs, comprising a feeding chute, a longitudinally reciprocating carrier, an anvil disposed to the rear of said carrier and provided with lateral abutment lugs, a pair of laterally disposed positioning means adapted for operative engagement with ends of the sections of springs operated on to impart partial rotation thereto, a pair of loop-forming heads arranged above said anvil and disposed one in advance of the other, a pair of vertically moving holding jaws associated with said anvil, and means for operating the carrier, looper heads, positioning means and holding heads in unison, substantially as set forth.

35. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with lateral abutment lugs, a pair of positioning means adapted to impart partial rotations to the sections of springs operated on, a pair of loop-forming heads arranged above said anvil and disposed one in advance of the other, a pair of vertically moving holding jaws associated with said anvil, and means for operating the carrier, looper heads, positioning means and holding heads in unison, substantially as set forth.

36. A mechanism for forming loops on sections of coiled springs, comprising a feeding chute, a longitudinally reciprocating carrier, an anvil disposed to the rear of said carrier and provided with lateral abutment

lugs, a pair of loop-forming heads arranged above said anvil and disposed one in advance of the other, a pair of vertically moving holding jaws associated with said anvil, means for imparting intermittent longitudinal reciprocation to the upper holding jaws, and means for operating the carrier, looper heads and holding jaws in unison, substantially as set forth. 70

37. A mechanism for forming loops on sections of coiled springs, comprising a feeding chute, a longitudinally reciprocating carrier, a spring finger and a stop finger associated with said chute in spaced relation and moving with said carrier, an anvil disposed to the rear of said carrier and provided with lateral abutment lugs, a pair of loop-forming heads arranged above said anvil and disposed one in advance of the other, a pair of vertically moving holding jaws associated with said anvil, means for imparting intermittent longitudinal reciprocation to the upper holding jaws, and means for operating the carrier, looper heads and holding jaws in unison, substantially as set forth. 80

38. A mechanism for forming loops on sections of coiled springs, comprising a feeding chute, a longitudinally reciprocating carrier, an anvil disposed to the rear of said carrier and provided with lateral abutment lugs, a pair of positioning means adapted to impart partial rotation to the sections of springs operated on, a pair of loop-forming heads arranged above said anvil and disposed one in advance of the other, a pair of vertically moving holding jaws associated with said anvil, means for imparting intermittent longitudinal reciprocation to the upper holding jaws, and means for operating the carrier, looper heads, positioning means and holding jaws in unison, substantially as set forth. 90

39. A mechanism for forming loops on sections of coiled springs, comprising a feeding chute, a longitudinally reciprocating carrier, an anvil disposed to the rear of said carrier and provided with lateral abutment lugs, a pair of laterally disposed positioning means adapted for operative engagement with ends of the sections of springs operated on to impart partial rotations thereto, a pair of loop-forming heads arranged above said anvil and disposed one in advance of the other, a pair of vertically moving holding jaws associated with said anvil, means for imparting intermittent longitudinal reciprocation to the upper holding jaws, and means for operating the carrier, looper heads, positioning means and holding jaws in unison, substantially as set forth. 100

40. A mechanism for forming loops on sections of coiled springs, comprising a feeding chute, a longitudinally reciprocating carrier, a spring finger and a stop finger associated with said chute in spaced relation and

moving with said carrier, an anvil disposed to the rear of said carrier and provided with lateral abutment lugs, a pair of positioning means adapted to impart partial rotations 5 to the sections of springs operated on, a pair of loop-forming heads arranged above said anvil and disposed one in advance of the other, a pair of vertically moving holding jaws associated with said anvil, means for 10 imparting intermittent longitudinal reciprocation to the upper holding jaws, and means

for operating the carrier, looper heads, positioning means, and holding jaws in unison, substantially as set forth.

Signed at Chicago, Illinois, this 12th day ¹⁵ of January 1914.
